UNITED STATES PATENT OFFICE.

WILLIAM D. MILLER, OF RAYWICK, KENTUCKY.

GATE.

1,131,408.

Specification of Letters Patent.

Patented Mar. 9, 1915.

Application filed September 18, 1913. Serial No. 790,426.

To all whom it may concern:

Be it known that I, WILLIAM D. MILLER, a citizen of the United States, residing at Raywick, in the county of Marion and State 5 of Kentucky, have invented certain new and useful Improvements in Gates, of which the following is a specification.

My invention relates to improvements in gates and refers particularly to the character or type of gates which swing and are opened and closed from either side by a person on foot or riding.

The main object of my invention is the provision of means for use in connection 15 with a swinging gate which will assist in the opening or closing of the gate, and which will effectively lock the gate when closed and positively prevent improper or accidental opening of the gate by contact from either side.

Another object of my invention is the provision of a combined lock and counterbalance which can be applied to swinging gates in general use or to such gates at the 25 time of erection, at a comparatively small cost, and which in every particular will prove efficient and practical.

With these objects in view, my invention consists of a gate and attachments embodying novel features of construction and combination of parts, substantially as disclosed herein.

In order that the detailed construction and operation of my improvements may be 30 fully understood and the many advantages be appreciated, I have illustrated in the accompanying drawing the best means I have at this time devised for the embodiment of my invention.

Fig. 1 represents a perspective view of a complete gate equipped with my improvement of attachment, the parts being in the position they occupy when the gate is closed. Fig. 2 is a side elevation on an enlarged 45 scale of the main parts of the lock and counterbalance, the parts being in the position they assume when the gate is closed. Fig. 3 is a similar view with the parts in the position they appear when the gate is open, and Fig. 4 is a sectional view on the line 4-4, of Fig. 2 the staple and link being omitted.

Referring by numerals to the drawing, in which similar characters of reference denote corresponding parts in all the views: The 55 numeral 1 designates portions of the fence, 2 the gate posts, 3 the gate swung by hinges

4, from one of the posts, and 5 the pair of posts or standards arranged on opposite sides of the gate, upon which by means of the brackets 6 and plates 7 pivoted therein 60 at 8, are mounted the pair of operating levers 9, to whose outer long ends are connected the cords or chains 10, for tilting or operating said levers from either side of the gate. From this construction, it will be observed that I provide a swinging gate, a post on each side thereof, and a pair of operating levers, and from the inner end of said levers depends a pair of chains 11, whose lower ends are connected at 12, to a 70 pair of arms 11' extending from a head 13, which head 13 is adjustably mounted upon the upper threaded end 14, of the link 15. This link or rod 15 is provided at its lower end with a loop or eye 16, which engages a 75 staple or bail 17 mounted in a counter-weight 18, which is rectangular in shape, and is provided in its upper portion with an opening 19, to receive one end of a rod 20, whose other end 21 is connected to the gate, and the weight 18 is further provided upon its under side with a pair of channels or recesses 22, in which is pivoted a forked or bifurcated end 22' of an arm 23, which has upon its other end a fork 24, pivoted upon a 85 post or support 25.

From the foregoing description, taken in connection with the accompanying drawings, the operation of my gate and attachment will be readily understood, and it will be at once apparent that when a person from either side of the gate draws down upon the connections which operate the levers, that said levers have their inner ends elevated, which elevation raises the link connected 90 with the lower ends of the levers, such raising of the link lifting the weight and permitting the gate when the weight is lifted and released to swing, and after the gate has been opened and passage effected, the 95 gate will automatically close, caused by the weight and attachment, or can be closed by the tilting of either lever. The pivotal connection of the rod 20 permits said rod and the arm 23 to swing in the different planes 100 during the swinging movement of the gate, as will be readily understood upon reference to Figs. 1, 2 and 3.

It will thus be seen that I dispense entirely with the usual fastenings in general 110 use, and provide a means which will assist in the opening and closing of the gate as

well as form a lock which will positively prevent the gate from opening accidentally, and also that the parts can be adapted to swinging gates in general use, or can be supplied with newly built gate, also that proper adjustment of the parts is provided to take up wear, and adapt the improvements to conditions, and that generally, by reason of the efficiency, durability, cheapness and simplicity of the invention, that a practical improvement is assured.

I claim:

In combination with a swinging gate, posts at each side thereof, operating levers fulcrumed upon said posts, a rod having its upper end adjustably and flexibly connected to said lever, a weight connected loosely to

the lower end of said rod and having a pair of longitudinal channels in its lower side and a single longitudinal opening in its upper portion, a rod having one end secured in said opening and its other end connected to the gate, a post, an arm having a forked end pivoted to the weight and fitting in the pair of channels in the lower side thereof, and its other end pivotally secured to said post.

In testimony whereof I affix my signature in presence of two witnesses.

WILLIAM D. MILLER.

Witnesses:

JAMES L. SPALDING,
L. P. SPALDING.
